UNITED STATES PATENT OFFICE.

KARL A. OLSON, OF PLAINFIELD, NEW JERSEY.

DIVING-BELL.

1,302,081.

Specification of Letters Patent. Patented Apr. 29, 1919.

Application filed September 25, 1918. Serial No. 255,650.

To all whom it may concern:

Be it known that I, KARL A. OLSON, a citizen of the United States, and residing at Plainfield, in the county of Union and 5 State of New Jersey, have invented certain new and useful Improvements in Diving-Bells, of which the following is a specification such as will enable those skilled in the art to which it appertains to make and use 10 the same.

This invention relates to diving bells for use in deep water and raising sunken ships, vessels and the like, and particularly to apparatus of this class having means for supporting a plurality of tools used for different purposes, and the object of the invention is to provide a pump apparatus hose coupling which is adapted to be supported by the tool supporting means and is secured to 15 the hull of a vessel whereby water may be pumped from the compartments of the sunken vessels and whereby air may be pumped into said compartments; a still further object of the invention being to provide 20 an improvement of this class which is simple in construction and operation and efficient in use; and with these and other objects in view the invention consists in a machine of the class and for the purpose 25 specified, constructed and operating as hereinafter described and claimed.

The invention described and claimed herein is an improvement on that described and claimed in a prior application filed by 30 me April 23, 1918, Serial No. 230,221, and is fully disclosed in the following specification, of which the accompanying drawings form a part, in which the separate parts of my improvement are designated by suitable 35 reference characters in each of the views, and in which:—

Figure 1 is a front view of a diving bell of the class specified with my improvement connected therewith;

Fig. 2 a partial section on the line 2—2 of Fig. 1 and on an enlarged scale and indicating the use of my improvement;

Fig. 3 a partial section on the line 3—3 of Fig. 2;

Fig. 4 a view similar to Fig. 1 but showing parts in a different position and on an enlarged scale;

Fig. 5 a partial section on the line 5—5 of Fig. 4;

Fig. 6 a partial section on the line 6—6 55 of Fig. 5;

Fig. 7 an enlarged sectional view of a part of a hull showing the first step of securing the hose coupling of a pump apparatus to the hull; 60

Fig. 8 a view similar to Fig. 7 but showing the second step; and,

Fig. 9 a view similar to Figs. 7 and 8 and showing the hose coupling secured to the hull. 65

In the drawing I have indicated at 10 a part of the hull of a diving bell, one face of which is provided with a plurality of magnets 11 usually employed in apparatus of this class, and at 12 I have indicated the 70 observation lenses of apparatus of this class.

In the practice of my invention, the hull 10 adjacent to the observation lenses 12 is provided with an enlarged bearing portion 75 13 through which passes the usual rotary member or shaft 14 which extends into the diving bell and is packed as shown at 15 and through which, in practice, is passed a rod 16 the inner end of which is packed as 80 shown at 17 and provided with an angular end portion 18, whereby the same may be rotated by a suitable wrench or crank, and the outer end of the rod 16 is threaded as shown at 19. The above named parts may 85 be of the usual or any desired construction and the end of the rotary member 14 is preferably provided with a conical or tapered aperture 20, the opposite side walls of which are provided with key apertures 21, which 90 extend the full length of said aperture as shown in Figs. 2 and 5.

The enlarged portion 13 of the hull is provided at one side of the rotary member 14 with an outwardly directed bearing 22 95 in which is rotatably mounted a shaft 23, the inner end portion of which is packed as shown at 24, and mounted on the inner end portion of said shaft and within the diving bell is a nut 25 having an enlarged base 100 flange 26 provided with a plurality of apertures 27 preferably four in number. A headed pin 28 is adapted to operate in connection with the apertures 27 in the flange

26 and with an aperture 29 in the hull 10 or the enlarged portion 13 thereof. The inner end of the shaft 23 is made angular in form as shown at 30, whereby a wrench, 5 crank or similar device may be connected therewith for rotating the same.

The outer end portion of the shaft 23 protrudes beyond the bearing 22 and secured to the protruding end thereof is a tool and 10 workpiece carrying member 31, consisting of an approximately semi-circular disk provided with a plurality of threaded apertures 32, 33 and 34 in which are adapted to be mounted respectively a drill 35, a tap 36, 15 and a hose coupling 37 of a pump apparatus.

The drill 35 is provided with a central threaded portion 38 rearwardly of which is an enlarged flange portion 39 having a reduced and conical head 40, the opposite 20 sides of which are provided with key ribs 41. The threaded portion 38 of the drill is adapted to enter the aperture 32 to support said drill in the workpiece carrying member 31, and the conical head 40 is adapted to 25 enter the conical recess 20 of the rotary member 14, and the face of the conical head 40 of the drill is provided with a threaded aperture 42 with which the rod 16, or the threaded end 19 thereof operates to retain 30 the drill in connection with the rotary member 14.

The tap 36 is also provided with a central threaded portion 43 rearwardly of which is an enlarged flange 44, having a conical head 35 45 provided at the opposite sides thereof with key ribs 46; and the face of the conical head portion is provided with a threaded portion 47. The connection of the tap 36 with the workpiece carrying member 31 and 40 with the rotary member 14 will be the same as the connection of the drill therewith, except that said tap is connected with the threaded aperture 33 in said carrying member.

The hose coupling 37 consists of a main 45 cylindrical body portion 48 having a central bore 49 which extends approximately the full length of the body portion and forms an externally threaded sleeve 50 at one end of said body portion, which is adapted to 50 be connected with the threaded aperture 34 of the workpiece carrying member 31 as shown in Figs. 1 and 2. Inwardly of the threaded sleeve portion 50 is an enlarged threaded portion 51 and the other end portion 55 of the body part 48 of the coupling is provided with an enlarged flange 52, having a central conical head portion 53 provided at its opposite sides with key ribs 54, and the face of the conical head portion 53 is 60 provided with a threaded aperture 55 with which the rod 16 of the threaded end 19 is adapted to be connected to retain the coupling in connection with the rotary member 14 as clearly shown in Fig. 2.

A supplemental cylindrical body portion 65 56 is rotatably mounted on the main body portion 48 of the hose coupling between the enlarged flange 52 thereof and a sleeve 57 secured to the threaded portion 51 as shown in Fig. 5. The supplemental body 70 portion is provided with an outwardly directed internally threaded sleeve portion 58 flanged as shown at 59 and with which is adapted to be connected a coupling sleeve 60 having a flexible tube 61, the other end 75 of which is connected with a suitable pump apparatus on a ship or vessel upon the surface of the water.

The supplemental body portion 56, or the inner face thereof is provided with an annular recess 62 forming a port or passage around the main body portion 48 of the hose coupling and said main body portion is provided with a plurality of radial apertures 63 which form a communication between the bore 49 and the port or passage 62, as clearly illustrated in Fig. 6 of the drawing, and in the operation of the pump apparatus the water from the sunken vessel or a compartment thereof is pumped through the bore 90 49, radial apertures 63 and port or passage 62 out through the internally threaded sleeve portion 58 through the coupling sleeve 60 and thus through the flexible tube 61.

In Figs. 7 to 9 inclusive, I have indicated at 64 a part of the hull of a sunken vessel and as shown in Fig. 1, and in the operation of my improvement, the diving bell is first lowered into the position adjacent to the hull in the usual manner and held in contact therewith by the magnets 11, after which the rotary tool holder 31 is rotated from within the diving bell by placing a crank on the angular end 30 of the shaft 23 to bring the drill 35 on said holder into alignment with the rotary member 14, and said drill and workpiece carrying member 31 is locked in this position by passing the pin 29 through the proper aperture 27, in the sleeve 26 and into the aperture 29, after which the rotary member 14 and rod 16 are manipulated to grasp the conical head 40 of the drill to retain it in said rotary member, after which said member is rotated to 115 detach the drill 35 from the workpiece carrying member 31 and to move it rearwardly out of engagement with said workpiece carrying member, after which said member is rotated to bring it into the position shown 120 in Fig. 4 to permit the free outward movement of the drill 35 on the end of the rotary member 14 and a hole 65 is thus drilled into the hull 64 of the sunken vessel.

After completing the above operation of 125 drilling the hole 65, the drill is moved inwardly to such an extent as to clear the inner face of the member 31, after which said

member is rotated to bring the threaded aperture 32 into alinement with said drill and the same is again connected with the member 31 by reversing the above operation.

5 The next step is to tap the hole 65 as shown at 66 in Fig. 8, which operation is accomplished by bringing the tap 36 into alinement with the rotary member 14 by

10 rotating the member 31 and detaching it from said member in the same manner as the detachment of the drill therefrom, and also in replacing it in the aperture 36 when the hole 65 has been tapped.

15 The next step of the operation is the placement or securing of the hose coupling 37 in the tapped hole 66 of the hull 64, as shown at 67 in Fig. 9, and in this operation the pump device is first brought into alinement with the rotary member 14, the conical-head portion 53 thereof connected with the conical aperture 20 of said rotary member, after which the pump device is detached from the member 31 and moved into the position shown in Fig. 5, or to clear the inner face of the member 31, after which said

20 member is rotated to bring it into the position shown in Figs. 4 and 5 to permit the hose coupling to pass outwardly of said member, and to be secured to the hull 64 of the vessel as shown in Fig. 9 of the drawing. As hereinbefore stated, after the hose coupling has been connected with the hull of the sunken vessel, or a compartment thereof,

25 a signal may be given to the operators of the ship or vessel controlling the raising and lowering of the diving bell and suitable pump apparatus put into operation to draw water from the hull or compartment in the hull of the sunken vessel, and after all of such water has been withdrawn air may be pumped into said vessel, or a compartment thereof by utilizing the same hose coupling, or an independent hose coupling may be 30 connected with the same compartment of the hull in the manner above described, and as the water is pumped out of such compartment air may be pumped thereinto by a suitable apparatus.

35 40 45 50 55 60 As hereinbefore stated, the supplemental body portion 56 of the hose coupling 37 is rotatably mounted on the main body portion 48, and this facilitates the connection of the main body portion with the hull without rotating the supplemental body portion 56, and said supplemental body portion may thus be held in an approximately vertical position by the flexible tube 61.

65 While I have shown the workpiece carrying member 31 as capable of supporting two tools and a single hose coupling, it will be understood that my invention is not necessarily limited to the number of tools or cou-

pling or other attaching devices secured thereto, nor am I necessarily limited to the specific means of connecting such tools and attaching devices with said supporting member; and various other changes in and modifications of the details of construction 70 herein shown and described may be made, within the scope of the appended claims, without departing from the spirit of my invention or sacrificing its advantages.

Having fully described my invention, 75 what I claim as new and desire to secure by Letters Patent, is:—

1. In an apparatus of the class described, a hose coupling adapted to be connected with the hull of a sunken vessel and comprising a main body portion having a central bore, and a supplemental body portion rotatably mounted on the main body portion and having a port or passage placed in communication with the bore of the main 80 body portion, a flexible tube coupled with said supplemental body portion, and the main body portion being provided with means to permit of its connection with the hull of a sunken vessel. 90

2. In a diving bell apparatus, involving a hull, the combination with the hull and a rotary member mounted therein and movable inwardly and outwardly therethrough, of a carrying member rotatably mounted in the hull adjacent to said rotary member, said carrying member being provided with a plurality of threaded holes for supporting a plurality of tools and attaching devices threaded to engage said threaded holes, 100 and means whereby the carrying member may be rotated to bring said tools and attaching devices into axial alinement with said rotary member. 95

3. In a diving bell apparatus involving a hull, the combination with the hull and a rotary member mounted therein and movable inwardly and outwardly therethrough, of a carrying member rotatably mounted in the hull adjacent to said rotary member, said carrying member being provided with a plurality of threaded holes for supporting a plurality of tools and attaching devices threaded to engage said threaded holes, means whereby the carrying member may be rotated to bring said tools and attaching devices into axial alinement with said rotary member, and means for locking said carrying member in such positions. 110 115

4. In a diving bell apparatus involving a hull, the combination with the hull and a rotary member mounted therein and movable inwardly and outwardly therethrough, of a carrying member rotatably mounted in the hull adjacent to said rotary member, said carrying member being provided with a plurality of threaded holes for supporting a plurality of tools and a hose coupling, 120 125

- means whereby the carrying member may be rotated to bring said tools and hose coupling into axial alinement with said rotary member, means for locking said carrying member in such positions, and means whereby said tools and a hose coupling may be detached from the carrying member by said rotary member and supported by said rotary member.
- 10 5. In a diving bell apparatus involving a hull and a rotary member mounted therein and movable inwardly and outwardly therethrough, a carrying member rotatably mounted in the hull adjacent to said rotary member, said carrying member being provided with a plurality of apertures for supporting a plurality of tools and attaching devices therein, means in the apertures of said carrying member and on said tools and 15 attaching devices for rigidly supporting said tools and attaching devices in connection with the carrying member, and means whereby the carrying member may be manipulated to bring said tools and attaching devices into axial alinement with said rotary member.
6. In a diving bell apparatus involving a hull and a rotary member mounted therein and movable inwardly and outwardly therethrough, a carrying member movably mounted in the hull adjacent to said rotary member, said carrying member being approximately semi-circular in form and provided with a plurality of apertures adapted 20 to support a plurality of tools and a hose coupling, means in said apertures and on said tools and hose coupling for rigidly sup-
- porting said tools and hose coupling in connection with said carrying member, means whereby the carrying member may be manipulated to bring said tools and hose coupling in axial alinement with said rotary member, and means on said tools, hose coupling and rotary member whereby said tools and hose coupling may be detached from the carrying member by said rotary member.
7. In a diving bell apparatus involving a hull, a rotary member mounted therein and movable inwardly and outwardly therethrough, a carrying member rotatably mounted in the hull adjacent to said rotary member, a hose coupling supported in said carrying member, said hose coupling comprising a main body portion having a central bore, and a supplemental body portion rotatably mounted on the main body portion and having air ports or passages placed in communication with the bore of the main body portion, and a flexible tube coupled with said supplemental body portion, and means whereby the carrying member may be moved to bring the main body portion of the hose coupling into alinement with said rotary member to permit of its connection therewith.
- In testimony that I claim the foregoing as my invention I have signed my name in presence of the subscribing witnesses this 21st day of Sept., 1918.
- KARL A. OLSON.
